UNITED STATES PATENT OFFICE

2,443,277

WINDOW CLEANER WITH WIPER FEEDER

Eugene Simor, New York, N. Y.

Application May 12, 1947, Serial No. 747,519

5 Claims. (Cl. 15—232)

1

This invention relates to window cleaners, and is an improvement on the window cleaner, for which Letters Patent of the United States have been issued to me, No. 2,313,367 dated March 9, 1943.

The main object of this invention is to provide means in cooperation with the window cleaner head of the type described in said patent, whereby the drying and polishing medium of the window cleaner may be easily and semi-automatically refreshed and replaced.

Another object of this invention is to provide a comparatively large supply of drying and polishing media right in the window cleaner head, said supply when used up being easily exchanged by a new one.

Still further objects of this invention will be apparent as the specification of the same proceeds, and, among others, I may mention; to provide a device as characterized hereinbefore, which will be simple in construction, and more efficient in operation, than the window cleaner described in my said patent, which will be easier and less expensive to manufacture, which will have better means for drying and polishing, and will have novel means for pivoting the head, and novel means for adjusting the length of the handle.

In the drawings forming a part of this specification and accompanying the same:

Fig. 1 is a plan view of my novel window cleaner head;

Fig. 2 is a side elevational view thereof, and Fig. 3 is a fragmentary sectional detail thereof.

As in the construction described in my said patent, the window cleaner will have a cleaner head proper, generally indicated by the numeral 10, which is pivotally mounted on a handle or leg, generally indicated by the numeral 11, its pivot construction being shown at 12.

The head 10 may be turned on the pivot 12 in practically any desired direction with reference to the handle 11, as has been amply described in my said patent, so that it may be in the position shown in the drawings wherein its plane is set transversely to the axis of the handle, and in that position it may be rotated so as to bring either the window washing element 13 into operative relation with the window pane or its frame to be cleaned, or to bring into such a relation the opposite end 14 of the cleaner head carrying the drying and polishing medium, as will be described more in detail hereinafter. On the other hand, the head may be turned with its plane in parallelism with the handle 11,

2

and its various cleaning elements may then be brought into engagement with the window pane or with the frame therearound, as will be obvious.

It also will be obvious that the handle 11 may be a simple elongated member by which the head 10 may be operated on the window pane or its frame, or the handle 11 may be continued in a U-shaped inner leg whereby it may be operated from the inside of the window to clean the outside thereof, as also has been amply described in said patent, and as it is well known.

My novel pivoted window cleaner head 10 in its improved construction shown in the drawings herein, will have a frame or base structure 15 being formed of one single piece of sheet material, and having a rectangular base proper 16, the left margin of which is turned inwardly as at 17, then upwardly as at 18, and outwardly as at 19, forming a channel, generally indicated by the numeral 20, into which is secured the said washing medium 13, in the embodiment shown being a sponge, and being secured by a plate or cord 21 formed into long stitches across the inner portion 13a of the sponge and passing through holes 22 in the upper and lower legs of the channel 20.

On the right hand side, the base proper 16 is simply bent upwardly into a transverse flat flange 23. A higher transverse flange 24 is secured across the base plate 16 at about the center thereof, having a foot portion 25 by which it is so secured through the rivets 25a, and an upper narrow center inwardly turned flange 26, the two ends 27 of which are wider and continue in downward terminations 28.

In the embodiment shown in the drawings, the leg or handle 11 of my device is shown as being formed of tubular members 29, 30, etc.; the top member 29 is the one which is pivotally connected to the head at 12, and for this purpose I provide a transverse screw 31 with a head 32 and a wing nut 33 threaded at the end thereof. A U-shaped connecting member 34 is secured on the reduced end 35 of the top leg member 29 by its downwardly turned branches while its base 34a will be pivotally secured to the base plate proper 16 by the screw 36, having a lower head 37 and the nut 38 threaded thereon at the top.

Appropriate washers are arranged under the head 37 and the nut 38, said upper washer preferably being made with an opening having a straight side and a portion of the screw 36 at said washer being flattened to prevent a relative rota-

tion of the nut 38 with respect to the screw 36 and its loosening.

It will be seen that by tightening the nut 38 to a desired degree, the head 10 will sit reliably on the handle 11 but still will be rotatably on its axis, as has been described in my said patent in connection with another pivot construction.

Also, by judicious operation of the wing nut 33, the U-shaped connecting member 34 may be turned on a transverse axis to the handle 11 carrying with it the whole head construction 10, whereby the hand may be turned in other desired manners, the combination of the two movements practically providing a universal joint between the handle 11 and the head 10, and permitting any desired positions for the head as will be obvious and has been described more in detail in said patent.

I also want to remark that in the embodiment shown, the handle 11 is made up of sections 29, 30, etc., the lower section in each case, as 30 in Fig. 2 having a reduced upper termination as 30a, secured in the lower end of the upper section, in said figure being indicated at 29, and a so-called bayonet lock 40 being provided for securing the lower section into the upper one. In the embodiment shown the lower section will carry a screw 41 similar to the screw 31 at the upper end of the handle 11. The lower end of the upper section 29 will have two registering angular slots 42.

When it is desired to connect the two members the respective portions of the screw 41 will be pushed upwardly, then transversely in the angular slot 42, whereupon a wing nut 43 may secure the parts together in a releasable manner.

With this construction longer or shorter handles with entirely reliable strong rigid connections of the sections may be built, according to the prevailing conditions at a certain window and to accommodate the person using my device.

The washing element, in this case the sponge 13 is used with my novel construction in a similar manner as has been in said patent, and as it is usual and will be understood. The head is turned with its plane parallel to the handle 11, the sponge 13 dipped into water, then pressed against a hard surface or preferably against a receiving container for the superfluous liquid, and a part of the water pressed out of it, whereupon the respective portion of the window may be washed by any appropriate movements and maneuvers of the head 10.

Now, the washed window pane has to be wiped, dried and polished. For this purpose a wiping and polishing member, generally indicated by the numeral 44 is arranged on and against the upstanding flange 23 of the head 10 at the opposite side to that of the washer 13.

I prefer to make the wiper or drier rectangular in cross section, having an elongated central, preferably wooden core 45, and two somewhat wider resilient rubber strips 46 placed against the same, and secured thereon by any appropriate means.

A plurality of layers 47 of a wiping and polishing sheet material is rolled around the rectangular wiper element 44, said sheet may be of any appropriate fabric, paper and the like. A pin 48 is secured in the center wooden core 45, having the two projecting ends 48a and a horizontal heavier pin or rod 49 is engaging each pin termination 48a, preferably by an inclined recess 50. The inner end 49a of the pin 49 projects beyond the upstanding flange or plate 24, said pin being slidable in a hole in said plate, as will be obvious.

A cross pin 51 is secured through the rod 49 and a coil spring 52 is interposed between the upstanding flange 23 and the cross pin 51.

It will be seen that the spring 52 will press the wiper 44 against the flange 23 with a yielding resilient action.

In the embodiment shown in the drawings, the outer free end 53 of the wiper fabric 47 is continued and secured and rolled on a roller 54, having a throughgoing pin 55 secured therein, one end of which is formed into a grip or handle 56. A rod 57 is slidably secured in the upper part of the plate 24, and in the downward termination 28 thereof for each pin end 55a engaging the same by an inclined recess 58 similar to the recesses 50 described in connection with the pins 48a, so that the used wiper sheet receiving roller 54 may be rotated in said inclined recesses of the rods 57. A cross pin 59 is secured under each horizontal slidable rod 57 and a coiled spring 60 is interposed between the same and the upstanding plate or flange 24, whereby the roller 54 will be pressed against the upper part of the plate 24 with a resilient yielding action.

The use and operation of my device will be obvious from the herein description and the showing of the drawings. However, I want to describe it more in detail as follows:

After the window pane has been washed, the outer surface 14 of the wiper 44 will be pressed against it with a desired judicious amount of pressure and operated thereon as necessary. When the outermost layer 47 on the exposed surface 14 becomes wet and used up, the wiper element 44 will be turned, as for instance, in the direction of arrow 61, whereby the surface 14 will now be the lower one on the wiper element 44 and its former upper portion will be the one adapted to be operated within the position indicated at 14. This turning may be executed by the user simply grasping the wiper element 44 between the thumb and finger and turning it as indicated. In that case the roller 54 will be turned in a similar direction as indicated by the arrow 62, so as to take up the slackness in the wiper sheet 53, as will be understood.

Another way of exposing a fresh side of the wiper 44 would be to turn the roller 54 as indicated, whereby the pull on the sheet 53 will cause the wiper element 44 to turn, and present a fresh surface for the wiping operation.

It will be seen that on account of the rectangular or square cross section of the wiper element, one side thereof will always be pressed against the upstanding flange 23, while the parallel flat side will do the wiping operation. In this manner the wiping may be done by a large surface and always in a safe rigid reliable manner.

When all the cleaner sheets 53 have been used up, the rods 49 may be pressed forwardly, as indicated by the arrow 63 thereby releasing the pin ends 48 from the slots 50, and the wiper element 44 may be lifted out of the same. In a similar manner the upper rods 57 may be pushed forwardly or outwardly, as indicated by the arrow 64, and the rolled up, used material 54 may be lifted off the recess or slot 58. In a similar manner new wiper elements 44 and roller 54 may be placed in my device.

It will be seen that several such replacements may be ready and may be placed into the device without any delay, so that my device may be used in a very efficient quick and easy manner, and then the cores of the used wiper element as well

as the rolled up used sheet roll 54 may be returned to a servicing place and fresh similar elements or units received.

However, the user may also unwind the used up or wet wiper sheet from the roller 54, then roll a fresh one around the core of the wiper 44, secure the end of it to the free roller 54, and replace them in the window cleaner head, as indicated in the drawing. In this manner no additional wiper elements or receiving rolls are needed, only a supply of fresh wiper sheets or bands.

It also will be obvious that instead of arranging the fresh wiper band around the wiper element 44 and rolling the same off of it on to the roller 54, the operation may be the reverse, and the fresh unused wiper sheet may be rolled up on the roller 54 and its outer end secured on the wiper member 44, whereupon when a portion of it will be used, the wiper element 44 will be turned, presenting a fresh side thereof for operation and pulling additional layers from the roller 54. The wiper element 44 may be turned by grasping the same, as has been described hereinbefore, or one of its pin terminations 48a may be formed into a grip similar to that indicated at 56.

For an easier release of the roller 54, its two rods 57 may be interconnected by a transverse rod 67 so that pressing that portion 57 forwardly, will release both pins 55a at the same time. Of course, similar interaction may be made between the lower rods 49a at the two sides of the device, which, however, was not shown in this drawing, and will be rarely used as it would be inconvenient for access.

I may also remark that layers 47 may be formed by a double sheet of appropriate material, one of them 70, being the wiper or drier material proper, while the other 71, may be a water repellent one, so that it may protect the next layer thereunder.

It will be obvious that with a straight handle instead of the usual U-shaped handle, my device may be used for cleaning floors, bathrooms, or for any other appropriate places, like cafeteria tables and mirrors, like tables and mirrors in restaurants.

While I have shown a preferred embodiment of my invention, it is to be understood that changes and variations may be resorted to in the elements, combinations and operation of my invention, and I reserve my rights to such changes and variations, as are within the spirit of this specification, and the scope of the claims hereunto appended.

What I claim as new and want to protect by Letters Patent of the United States is:

1. In a window cleaner, having a cleaning head proper, a first rotatable wiper member having a sheet of wiping means secured thereon by one end and wound therearound, a second rotatable member in parallelism with said first member

having the other end of said sheet wiper means secured thereon adapted to be wound therearound, whereby rotating one member will cause said wiper sheet to be wound thereon and to be unwound from the other, pins for the rotating members, transverse rods slideable in the cleaner head and adapted to rotatably receive and support said pins, a stationary element in said head for each rotating member, and spring means acting on said slideable rods whereby said rotatable members will be pressed against said stationary elements in a resilient yielding manner.

2. A device, as set forth in claim 1, wherein said stationary element for the first rotating member is in the form of a transverse flange along the respective edge of the cleaner head, and said first rotating wiper member has a square cross section whereby the same will present one side thereof for wiping operations, the opposite side of the same being pressed against said flange, and whereby the same may be rotated with its respective corner rotating against said flange and its respective flat side automatically arranging itself flat on said flange.

3. In a device, as set forth in claim 1, slots in said rods adapted to receive said pins whereby said pins may be lifted off said rods when the wiping medium is to be exchanged.

4. In a device, as set forth in claim 1, inclined slots in said rods adapted to receive said pins whereby said pins will be rotatably secured in said rods, but may be lifted off the same when desired.

5. In a device, as set forth in claim 1, slots in said rods to receive said pins whereby said pins may be lifted off said rods when desired, a transverse rod connecting the forward ends of the slideable rods for the first rotating member whereby they may be pressed simultaneously against the springs acting thereon, when it is desired to lift the roller pins off them.

EUGENE SIMOR.
